DESIGN FOR A TEXTILE FABRIC

Moses F. Gantz, Yonkers, N. Y., assignor to The
First Textile Corporation, New York, N. Y.

Application November 4, 1935, Serial No. 59,357

Term of patent 3½ years

To all whom it may concern:

Be it known that I, Moses F. Gantz, a citizen of the United States, residing at Yonkers, in the county of Westchester and State of New York, have invented a new, original, and ornamental Design for a Textile Fabric, of which the following is a specification, reference being had to the accompanying drawing, forming part thereof.

Figure 1 is a top plan view of the fabric, and Figure 2 is a side elevation of the fabric shown in Figure 1.

The characteristic feature of my design resides in a series of crinkled conical elevations arranged in parallel rows, the elevations of one row being in staggered relation to the preceding and succeeding rows.

I claim:

The ornamental design for a textile fabric as herein shown and described.

In testimony whereof, I hereunto affix my signature.

MOSES F. GANTZ.
